UNITED STATES PATENT OFFICE

ROSCOE D. POOLE, OF DANVERS, MASSACHUSETTS

ROUGH-ROUNDING MACHINE

Application filed January 12, 1929. Serial No. 332,123.

My invention relates to rough rounding machines such as are employed to trim the marginal portions of the outersoles of boots and shoes during the process of manufacturing the latter, and it has for its object to provide an improved machine of this class.

To this end I have provided an improved rough rounding machine having the peculiar features of construction and mode of operation set forth in the following description, the several novel features of the invention being particularly pointed out and defined in the claims at the close thereof.

In the accompanying drawings:

15 Figure 1 is a side elevation of a rough rounding machine constructed in accordance with my invention.

Figure 2 is a sectional detail, full size, relating to the anvil mechanism hereinafter described.

Figure 3 is a plan view, partly broken away and in section, of the machine shown in Fig. 1.

Figure 4 is a section on line 4—4 of Fig. 1.
25 Figure 5 is a plan view, full size, of the rotatable anvil.

Figure 6 is a section on line 6—6 of Fig. 2.

Figure 7 is a side elevation, full size, of the lower portion of the knife hereinafter described.

Figure 8 is a front elevation, full size, of the lower portion of the knife hereinafter described.

Figure 9 illustrates the shape of the cutting edge of the knife shown in Figs. 7 and 8.

Figure 10 is a plan view, partly in section, of a portion of the rear end of the machine showing part of the actuating mechanism for the rotatable anvil.

40 Figure 11 is a detail hereinafter described.

Having reference to the drawings, 10 is the frame of my improved rough rounding machine, said frame being adapted to be fixed in position upon a bench or other suitable support. Fulcrumed on this frame at 45 11 is a lever 12 having a rearwardly extending arm formed with a slot 13 within which are slidably mounted two half-bearing blocks 14 which embrace a crank 15 that is part of a main drive shaft 16. At their rear

ends the two branches or arms of this rearwardly extending slotted arm are held against spreading or yielding by means of a bolt 17.

The other forwardly extending arm of lever 12 is made at its free end with a head 18 having an outer arcuate face formed with an arcuate slot 19 that is concentric with the axis of the fulcrum pin 11. Within this slot 19 is arranged and fitted a correspondingly curved knife 20 which is clamped rigidly to the head 18 by means of a plate 21 and screws 22.

The lower end of knife 20 is made with a cutting edge 23 and co-operates with a circular anvil 24 herein shown as a conical disk fixed rigidly to the upper end of a short vertical spindle or shaft 25 by means of a pin 26 and screw 27. Shaft 25 is journaled in a bracket made up of an arm 27, sleeve 28 and box 29, the arm 27 being formed with two parallel slots 30 to accommodate two screws 31 by means of which the bracket is clamped fixedly to frame 10 but with provision for adjustment in a direction that varies the position of the knife radially with respect to the anvil 24.

As will be clear from Figs. 1 and 5, the arcuate cutting edge 23 is disposed in and crosswise of a vertical plane coincident with the axis of anvil 24 and parallel with the slots 30, so that when the screws 31 are loosened and arm 27 is adjusted on frame 10 the cutting position of the knife is varied radially with respect to the anvil 24. Thus the anvil 24 can be positioned so that the cutting edge 23 of the knife will cooperate with said anvil at any desired distance inwardly from the outer periphery thereof within the limits of the slots 30.

The upper end of the sleeve 28 is forced into the arm 27 thereby rigidly and permanently joining the two, while the box 29 is fixed rigidly to the lower end of sleeve 28 by a screw 32.

The box 29 serves as a housing for a ratchet wheel 33 and pawl carrier 34, Figs. 2 and 6, mounted upon the lower end of shaft 25, the former being keyed to said shaft by a pin 35 while the latter is loosely mounted

thereon. Ratchet wheel 33 and pawl carrier 34 are held in position on shaft 25 by the head of a screw 36. Spring pressed pawls 37 of different lengths are provided upon the top side of carrier 34 to cooperate with ratchet wheel 33.

The pawl carrier 34 has pivotally connected to it the forward end of a connecting rod 38 whose rear threaded end extends through and is in threaded engagement with a block 39 swivelly connected to one arm of a bell-crank lever 40 fulcrumed at 41 on frame 10. This lever 40 is within the frame 10, and its other horizontally disposed arm 10 is directly below and in the path of the rearwardly extending slotted arm of lever 12 so that it is bunted by the latter during each downward stroke thereof. Thus during each revolution of main shaft 16 the bell crank 40 is swung in one direction by lever 12 and in the opposite direction by a spring 42 whereof one end is connected with the rear end of rod 38 and the opposite end with frame 10. The lever 12 always swings the bell-cránk 40 to the same position at the limit of its movement in one direction, but the movement of said bell-cránk in the opposite direction under the influence of spring 42 is limited by an adjustable stop 43 herein shown as an eccentric provided at the inner end of a spindle 44 journaled in a bearing provided in one of the side walls of frame 10. Thus by rotative adjustment of stop 43 the extent of movement imparted to bell-cránk 40 by lever 12 and spring 42 can be varied.

It will be clear that the vibration of bell-cránk 40 thus occasioned by lever 12 acts through rod 38 to oscillate pawl carrier 34 whose pawls 37 act through ratchet wheel 33 and shaft 25 to rotate anvil 24 step-by-step in the direction indicated by the arrow in Fig. 5.

As shown in Fig. 10, the outer end portion of the spindle 44 has fixedly mounted thereon a hand wheel 45 made with a tubular hub within which is arranged a compressed coiled spring 46 that yieldingly holds the stop eccentric 43 against the adjacent side wall of frame 10 thereby preventing its accidental rotative displacement.

Rotative movement or displacement of anvil 24 otherwise than by pawls 37 is prevented by means of friction brakes herein shown as felt pads 47 compressed against opposite sides of shaft 25 by screws 48, each screw and its pad being mounted within a radial cylindrical chamber provided in arm 27.

The knife 20 is positioned on lever 12 so that when the forwardly extending arm of the latter is at the limit of its movement toward anvil 24 the cutting edge 23 of the knife is in contact with the top surface of said anvil. It follows, therefore, that said

cutting edge will be driven entirely through a piece of stock resting upon the top of anvil 24 when it is carried downwardly by the lever. In order to provide for accurately, conveniently and quickly positioning the knife as described, the upper end of the latter is made with a laterally extending forked arm 49 occupying a groove 50 provided upon a thumb-screw 51 whose threaded shank occupies a threaded hole formed in head 18. It will be clear that after loosening screws 22 the knife 20 can be accurately adjusted endwise in its groove 19 by rotation of thumb screw 51.

At 52 is shown a presser-foot lever that is pivoted at 53 to a bracket 54 rigidly fastened to frame 10. At one side of pivot 53 the presser foot is made with a chamber 55 containing a coiled spring 56 whose lower end bears upon the top of bracket 54 and whose upper end bears against an adjustable abutment screw 57. At the opposite side of pivot 53 the presser-foot 52 carries an adjustable stop screw 58 that is yieldingly urged toward, or held against, bracket 54 by spring 56 while at the same time the front working-engaging arm of the presser-foot is yieldingly urged downwardly toward anvil 24.

The main shaft 16 carries a loose pulley 59 and a tight pulley 60 to co-operate with a continuously running, power-driven belt, not shown, which drives shaft 16 at a high rate of speed when engaged with tight pulley 60.

The arms of bell-cránk 40 are provided with abutment fibre pads 61 and 62 to co-operate, respectively, with lever 12 and stop 43, said pads minimizing both noise and wear.

In trimming the sole of a shoe the latter is presented to the machine upside down with the margin of the sole occupying a position on top of anvil 24; with the presser-foot bearing upon the topmost, or tread, side of the sole and with the peripheral edge of the anvil 24 snugly fitted into the inseam. When the machine is started with the shoe held in this position by the operator the lever 12 is rapidly vibrated while the anvil is rotated step by step. As the shoe is thus fed past the knife and anvil the operator assists in guiding the same and also swings it around at the heel and toe, at all times pressing the shoe sidewise against the anvil.

Since the cutting edge of the knife is arcuate and positioned with its concaved side nearest or facing the axis of the anvil, it will now be clear that in traversing the inward curves at the shank of the sole, a smoothly cut edge is produced on the sole which would be impossible with a knife having a straight cutting edge. At the same time the edges produced upon the sole to the rear, and forward, of the shank are smooth and even, since each step movement imparted to the

anvil and work is much less than the length of the cutting edge of the knife.

As shown in Fig. 5, the marginal portion of the top surface of the anvil is knurled or roughened as at 64 to avoid slipping of the shoe on the anvil and to ensure movement of the shoe with the latter.

It is a feature of my new machine that the vibrating lever 12 is fitted snugly between two large bearings 65 and 66, Figure 3, with bronze washers 67 interposed between the hub of lever 12 and said bearings and with the latter provided with bushings 68, Figures 1 and 3, for the pivot pin 11. This pivot pin 11 is fastened to the lever 12 by a screw 69, and therefore rocks within the bushings 68 when the lever 12 is vibrated.

It is also a feature of the construction herein illustrated that the crank 15 is an integral part of the shaft 16 and the latter is provided with trunnion or journal portions at each end of the crank 15 which are mounted within bushings provided in very substantial bearings 70 on the frame of the machine. Therefore the crank 15 is substantially supported at both ends thereof.

With the machine constructed in this fashion the lever 12 can move only in a vibratory fashion and is firmly held against movement in any other direction.

What I claim is:

1. A sole trimming machine comprising a rotatable anvil wheel having a flat sole-supporting surface and a shoe-guiding periphery; a chopping knife; a movable carrier by which said knife is supported opposite and edgewise with respect to the flat sole-supporting surface of said anvil; means for operating said carrier to impart edgewise reciprocating motion to the knife thereby to cause the same to chop entirely through the marginal portion of the sole while the portion of the latter that is being operated upon by the knife is directly supported against the thrust of the knife by said anvil, and means for positively rotating said anvil wheel to feed the shoe past said cutter.

2. A sole trimming machine constructed in accordance with claim 1 wherein the means for positively rotating the anvil wheel actuates the latter step-by-step in alternation with the cutting strokes of the knife.

3. A sole trimming machine constructed in accordance with claim 1 wherein the means for positively rotating the anvil wheel actuates the latter step-by-step in alternation with the cutting strokes of said knife, and wherein there is also provided means for regulating the extent of angular movement imparted to said anvil wheel during each step movement thereof.

4. A sole trimming machine constructed in accordance with claim 1 wherein the means for positively rotating the anvil wheel actuates the latter step-by-step in alternation

with the cutting strokes of the knife and is itself actuated by said carrier in timed relation with said cutting strokes.

5. A sole trimming machine constructed in accordance with claim 1 wherein the means for positively rotating the anvil wheel actuates the latter step-by-step in alternation with the cutting strokes of said knife, and wherein there is also provided a friction brake for yieldingly opposing rotary movement of said anvil wheel.

6. A sole trimming machine constructed in accordance with claim 1 wherein the means for positively rotating the anvil wheel includes a member that is bunted in one direction by said carrier; a spring for returning said member in the opposite direction, and pawl and ratchet mechanism through which said member actuates said anvil wheel step-by-step in alternation with the cutting strokes of said knife.

7. A sole trimming machine comprising an anvil having a shoe-guiding edge and a flat sole-supporting surface; a chopping knife having an arcuate cutting edge which is parallel and approximately coincident with said sole-supporting surface at times and whose convex side faces said shoe-guiding edge; a movable carrier by which said knife is supported opposite and edgewise with respect to said flat sole-supporting surface of said anvil, and means for operating said carrier to impart edgewise reciprocating motion to said knife thereby to cause the same to chop entirely through the marginal portion of the sole while the portion thereof that is being operated upon by the knife during its cutting stroke is directly supported against the thrust of the latter by said anvil.

8. A sole trimming machine constructed in accordance with claim 7 wherein, with respect to the knife and anvil, one of said elements is adjustable relatively to the other in a direction parallel with said sole-supporting surface to vary the distance between said shoe-guiding edge and said knife edge.

9. A sole trimming machine constructed in accordance with claim 7 wherein, with respect to the knife and anvil, one of said elements is adjustable relatively to the other to vary the distance between said shoe-guiding edge and said knife edge.

10. A sole trimming machine comprising a rotatable anvil wheel having a flat sole-supporting surface and a shoe-guiding periphery; a chopping knife having an arcuate cutting edge which is parallel and approximately coincident with said sole-supporting surface at times and whose convex side faces said shoe-guiding periphery; a movable carrier by which said knife is supported opposite and edgewise with respect to said flat sole-supporting surface; means for operating said carrier to impart edge-

- wise reciprocating motion to said knife thereby to cause the same to chop entirely through the marginal portion of the sole while the part thereof that is being operated upon by the knife during each cutting stroke is directly supported against the thrust of the latter by said anvil wheel; a bracket on which said wheel is journaled, said bracket being adjustable to vary the distance between said shoe-guiding periphery and said knife; a lever operated by said carrier, and pawl and ratchet mechanism through which said lever rotates said wheel step-by-step in timed relation with the movements of said knife.
- 10 11. A sole trimming machine comprising a base provided with a pair of upstanding spaced apart bearing lugs; a rotatable anvil wheel having a horizontal flat sole-supporting surface and a shoe-guiding periphery; said wheel being rotatably mounted on said frame; a chopping knife co-operating with said anvil wheel; a lever pivotally mounted between and in engagement with said upstanding bearing lugs, said lever having an arm extending in one direction formed with a slot that is closed at its opposite ends and having another arm extending in another direction on which said chopping knife is mounted opposite and edgewise with respect to the flat sole-supporting surface of said anvil; a shaft journaled in two separated bearings on said frame and formed with a crank disposed between said bearings and occupying the slot of said lever, and means for rotating said shaft to cause the crank to vibrate the lever thereby to impart an edgewise reciprocating motion to the knife so that its cutting edge is carried up to and away from said flat sole-supporting surface of the anvil wheel.
- 20 25 30 35 40
